Primary Examiner — Cynthia Ramirez*Assistant Examiner* — Llorellys Martinez-Rivera(74) *Attorney, Agent, or Firm* — Hollingsworth Davis, LLC**CLAIM**

We claim the ornamental design for an optical diffuser, as shown and described.

DESCRIPTION

FIG. 1 is a front perspective view of an optical diffuser showing the present invention;

FIG. 2 is a front elevation view thereof;

FIG. 3 is a side elevation view thereof;

FIG. 4 is a top plan view thereof;

FIG. 5 is a bottom plan view thereof; and,

FIG. 6 is a front perspective view thereof, showing the optical diffuser in an environment of use.

The broken line portions shown in FIGS. 1 through 6 illustrate environmental subject matter only and form no part of the claimed design.

1 Claim, 5 Drawing Sheets(56)
